[57] CLAIM

The ornamental design for restraint latch for trucks, as shown.

DESCRIPTION

FIG. 1 is a front perspective view of a restraint latch for trucks showing my new design;

FIG. 2 is a rear perspective view thereof;

FIG. 3 is an enlarged side elevational view thereof;

FIG. 4 is an enlarged side elevational view of the side opposite that shown in FIG. 3;

FIG. 5 is an enlarged front elevational view thereof;

FIG. 6 is an enlarged rear elevational view thereof; and,

FIG. 7 is an enlarged top plan view thereof, with the release arm shown broken away for convenience of illustration, the bottom view being plain and unornamented.

FIG. 1

FIG. 2

FIG. 3

FIG. 4

FIG. 5

FIG. 6

FIG. 7
